UNITED STATES PATENT OFFICE

RENÉ JEAN GABRIEL CHARLOT, OF PARIS, FRANCE, ASSIGNOR TO THIBAUD GIBBS & CIE, OF PARIS, FRANCE, A CORPORATION OF FRANCE

SHAVING SOAP CASE

Application filed December 28, 1931, Serial No. 533,505, and in France January 9, 1931.

My invention has for its object a case for shaving soaps of the type comprising three elements, to wit a central ring-shaped part and two similar covers adapted to be screwed on or otherwise secured to either side of the central ring, each cover serving in alternation as a holder when the other is removed for allowing the shaving soap stick to be used.

Now according to my invention the ring 10 is formed of two half rings each provided with projections adapted to engage the soap to a somewhat considerable depth and to hold it securely without allowing it to slip.

I have shown by way of example in the 15 accompanying drawing two forms of execution of my invention.

Fig. 1 is a partly cross-sectional side view, of a first form of execution of my case.

Fig. 2 shows the two-part ring alone,

Fig. 3 is a corresponding plan view.

Fig. 4 is a cross-section of the ring.

Fig. 5 is a side view of a modification of the ring.

Fig. 6 is a corresponding plan view.

Fig. 7 is a cross-section of the modified ring.

The case comprises three different parts, a central ring-shaped part 1 divided into two halves and two similar covers 2 and 3.

The ring 1 comprises a central annulus 4 30 on either side of which are provided threaded cylindrical portions 5, 5'. One of the half rings constituting the ring forms at each end a bevelled male projection 6, while the other half-ring has at each end a female recess 35 7 cut to a corresponding shape. Obviously each half-ring may as well have one end forming a male part and the other a female part. In either case I obtain when mounting the two half rings an easy and rapid centering.

Moreover each half-ring shows an inner 40 projecting part 8—9. The two covers 2 and 3 are hollow and are screwed respectively over the threads 5 and 5' of the ring 1.

The case is used as follows: the case is dis- 45 mantled and the soap stick 10 held through its middle between the two half-rings, the projections 8 and 9 engaging the soap and ensuring a rigid fixation thereof; the covers 2 and 3 are then screwed over the threads 5 and 5'.

When it is desired to use the stick, one of these covers 2 is unscrewed and the soap is held through the other cover 3 forming a holder which owing to its comparatively great length may be comfortably held in the 55 hand. When half the soap originally contained in the case has been used, the cover 2 serves in its turn as a holder and part 3 forms the removable cover; I allow thus the soap stick to be completely used which is not the 60 case with the soap holders used heretofore.

The covers and/or the ring may be of any suitable material, chiefly of plastic material such as bakelite which allows the ring in particular to be given a certain thickness 65 where it is easier to mount the case.

Figs. 5, 6 and 7 show a modification allowing a still greater accuracy in the centering of the two half-rings. On one of these half rings, say 1, the annulus, 4 projects at 11 beyond the bevelled male end, while on the corresponding female part of the half-ring 1' the annulus remains slightly behind the bottom of the recessed part so as to leave a space 12 free for housing the projection 11. 70 The drawing shows a male part at one end and a female part at the other, but of course as in the case of Figs. 1 to 4, one of the half rings may show at both ends male parts and the other female parts.

What I claim is:

1. In combination with a container for soap sticks and the like small cylindrical bodies comprising two opposed covers having an inner thread at their periphery, the provision of two independent half-rings each provided with two outer threads for engaging the threads in the two covers respectively and comparatively deep projections raised on the inside of and substantially in the 85 middle of each half-ring for engaging the soap-stick or like body.

2. In combination with a container for soap sticks, and the like small cylindrical bodies comprising two opposed covers having an inner thread at their periphery, the provision of two independent half-rings each provided with two outer threads for engaging the threads in the two covers respectively, male and female interengaging parts pro- 90 95 100

vided on the adjacent ends of the half rings and comparatively deep projections raised on the inside of and substantially in the middle of each half ring for engaging the soap-stick or like body.

3. In combination with a container for soap sticks and the like small cylindrical bodies comprising two opposed covers having an inner thread at their periphery, the provision of two independent half-rings each provided with two outer threads for engaging the threads in the two covers respectively, male and female interengaging parts provided on the adjacent ends of the half rings, half annuli formed on the outside of the half rings, angularly shifted with reference thereto and adapted to abut again one another through their adjacent ends, and comparatively deep projections raised on the inside of and substantially in the middle of each half ring for engaging the soap stick or like body.

In testimony whereof I affixed my signature.
